UNITED STATES PATENT OFFICE

116,372

DESIGN FOR A CULINARY CABINET

Thomas B. Lynch and Clarence W. Kenzie,
Irons, Mich.

Application November 9, 1938, Serial No. 80,974

Term of patent 7 years

To all whom it may concern:

Be it known that we, Thomas B. Lynch and Clarence W. Kenzie, citizens of the United States, residing at Irons, in the county of Lake and State of Michigan, have invented a new, original, and ornamental Design for a Culinary Cabinet, of which the following is a specification, reference being had to the accompanying drawing, forming a part thereof, in which:

Figure 1 is a front perspective view of a culinary cabinet showing my new design;

Figure 2 is a top plan view thereof; and

Figure 3 is a front elevational view thereof.

The distinguishing, essential and dominant features or characteristics of the design are the inwardly downward slope of the top and the disposition of the strengthening ribs in the front door of the cabinet, all as shown.

We claim:

The ornamental design for a culinary cabinet, substantially as shown and described.

THOMAS B. LYNCH.
CLARENCE W. KENZIE.
